UNITED STATES PATENT OFFICE.

ROGER L. STROBEL, OF EAST HELENA, MONTANA, ASSIGNOR TO AMERICAN SMELTING AND REFINING COMPANY, A CORPORATION OF NEW JERSEY.

MUFFLER-BURNER.

1,376,979.

Specification of Letters Patent. Patented May 3, 1921.

Application filed May 2, 1919. Serial No. 294,252.

To all whom it may concern:

Be it known that I, ROGER L. STROBEL, a citizen of the United States, and resident of East Helena, in the county of Lewis and Clark and State of Montana, have invented certain new and useful Improvements in Muffler-Burners; of which the following is a specification.

My invention relates to an ignition device for firing the charge of ore on a moving grate, such as is found in a Dwight-Lloyd sintering machine and constitutes an improvement in the similar device disclosed in the patent to John F. Austin, No. 1,179,390, granted April 18, 1916.

It is usual in such constructions to position an open bottom muffle or hood across the top of the moving charge to be fired and eject burning fuel into the muffle in such a manner that the down draft of air through the charge on such machines will draw the flames down onto the charge to ignite the same.

Difficulty has been experienced in effecting a uniform ignition across the entire width, as the charge is fed.

Accordingly, the primary object of the invention is to provide a simple form of ignition device of the class outlined which will insure a through ignition of the charge across its entire face under all service conditions and which will effect this ignition economically and with the least possible destructive action on the parts subjected to the heat of the fired charge and of the ignition device.

Such devices are usually formed of a metallic frame hung above the moving grate and lined with tiles of some fire resisting material. Heretofore, the metal parts have been exposed to the intense heat present with the result that the frame burns off at its exposed parts allowing the lining material to fall upon the moving charge.

Accordingly, another object of the invention is to provide a device of the class described in which the exposed parts of the metal are minimized and protected as far as possible from the action of the heat.

Among the other objects of the invention is to provide an ignition device formed largely of separate blocks which can be readily replaced in the supporting frame, which cannot accidentally drop from the

frame and which will maintain a gas tight fit along the upper sides while permitting the expansion and contraction incidental to such structures when in active use.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

Referring to the accompanying drawings:

Figure 1 is a plan view looking down upon a preferred embodiment of the invention and with one end broken away to show internal construction;

Fig. 2 is a view in side elevation of the device shown in Fig. 1;

Fig. 3 is a longitudinal sectional view taken centrally through the device shown in Figs. 1 and 2;

Fig. 4 is an end elevational view at the left hand side or burner end of the device shown in the preceding figures;

Fig. 5 is a transverse sectional view taken on the line 5—5 of Fig. 2;

Fig. 6 is an end elevational view at the right hand end of the device shown in Figs. 1 and 3; and

Figs. 7, 8 and 9 are each perspective views of one element of the several arch sections, taken in order from left to right in their corresponding positions in the supporting frame; Fig. 7 being one of the two left hand arch sections; Fig. 8 being one of the intermediate arch sections and Fig. 9 being one of the right hand end arch sections.

The device is made up mainly of a fire block construction formed of arch blocks, such as are shown in Figs. 7, 8 and 9 assembled in a supporting metal frame. The metal frame comprises a series of upstanding, longitudinally spaced apart arch ribs 10, one rib disposed adjacent each end of the block sections hereinafter more fully described, and with the ribs fastened together to form a skeleton frame. The ribs are arch shaped as shown more particularly in Figs. 4 to 6 and are each formed of a pair of angle irons bent to form an upstanding

side 12, a top part 13 and an upwardly projecting extension 14. These angle irons are each disposed with a flange 15 projecting outwardly and adjacent flanges about opposite sides of a gusset plate 16 and fastened together by means of through bolts 17. These outwardly extending parts provide, in addition to their reinforcing functions, extensive areas of surface which act as heat 10 distributing areas tending to distribute the heat which contacts with the lower, exposed ends of the ribs. The ribs are connected along opposite sides by means of deep plates 18 forming side sills fastened to the inner 15 flanges 19 of the ribs by means of bolts 20. The ribs are also fastened in position adjacent the inner portions of the parts 13 by means of a center sill 21, bolted between the upward extensions 14 of the ribs. Eye 20 plates 22 are positioned between and fastened to the upper ends of the extensions 14 and are provided with eyes 23 providing means for hanging the device in position. These plates at the ends of the sections, 25 other than the ends of the device, are additionally utilized to fasten one extension 14 of one pair of ribs to the next adjacent extensions, thus assisting the center sill to hold the upper parts of the ribs in place. 30 The open skeleton frame thus formed has the side sills fixed in position relative to each other and provides a rigid support for the arched construction of fire resisting material hereinafter described. This metallic 35 skeleton frame also provides the support for a J-shaped bracket 24 at the left or burner end of the device. This bracket is utilized for the purpose of supporting a burner or other fuel discharging nozzle common in 40 such devices for the purpose of discharging combustion-supporting fuel into the interior of the device. The device is provided with a fuel conducting chamber extending lengthwise thereof and which can be divided 45 into an open bottom combustion chamber 25 and a closed bottom burner containing compartment 26. The compartment 26 is formed in a burner section 27 confined within the outlines of the two end arch ribs 50 at the left of the device. These ribs project downwardly below the other ribs and are each provided on the inner flanges with L-plates 28 constituting supports for a floor plate 29 bridging the space between the opposite sides 12 of these ribs. The lower ends 55 of these ribs are tied together by a pair of connecting rods 30. The fire resisting part of the device containing the chamber 25 and compartment 26 is formed of three pairs of 60 arch blocks, each slightly different from the others. The first pair at the left end of the device is made up of two of the blocks shown in Fig. 7 and coact to form the sides and top of the burner containing section 27. 65 This compartment, as will be noted from

Fig. 1, is outlined on opposite sides by upstanding walls 31 and is of progressively greater cross-sectional area from the inlet end 32 toward the opposite or inner end. All of the sections are provided with interlocking tongue and groove joints 33 along the crowns 34 of the arches. The blocks are provided at their inner ends with similar interlocking joints 35 so that the blocks are interlocked in pairs across the crown of the arch and one pair is locked to the next adjacent pair. While the structure is thus made up of separate blocks, they coact to form a solid structure in which gas leakage through the upper portion of the structure is avoided. The intermediate arch structure is formed of a pair of the arch blocks 36 shown in Fig. 8 and the right end arch structure is similarly formed of a pair of the arch blocks 37 shown in Fig. 9. 70 75 80 85

The upper arched wall constituting the crown of the assembled arch structure converges downwardly from the flame inlet end 26 of the combustion chamber 25 toward the opposite end 39. This opposite end is substantially closed by a depending wall 40 except for an outlet 41 of small dimension extending slightly above the plane of the bottom edge 42 of the blocks 36 and 37. The lower edges of the intermediate and right end arch sections are provided with broad flat surfaces 43 disposed in a single plane so that the right hand portion of the structure may be positioned relatively close to the grate on the sintering machine shown in 90 dotted outline in Fig. 3. This construction provides a relatively wide and long outlet which extends entirely across the moving grate of the sintering machine and due to the tapered shape of the combustion chamber 100 tends to cause an even distribution of flame throughout the entire length of the opening. The bottom of the compartment is closed by means of a pair of flat blocks 44 positioned on the plate 29 fitted between 105 the two left end ribs and engaging the lower face 45 of the arch blocks at the left end of the device. 110

In operation, the device is hung above the sintering machine as is usual in such operation and with a suitable burner in the burner containing chamber, the burner is started in active operation, so as to eject burning fuel into the combustion chamber. The fuel contacting with the inclined wall 115 of the chamber is reflected down on top of the moving charge of ore igniting the charge as is usual in such operations. 120

By means of a device of this character an efficient combustion is attained with a resulting saving in fuel and but little heat is lost as radiation has been reduced to a minimum and the jointed structure minimizes leaks. The ignition of the charge as it is passed under the muffler is uniform, taking 125 130

place entirely across the pallet and especially igniting that part of the charge which is next to the side of the pallet.

But little metal is exposed either to the heat within the combustion chamber or to the heat from the fired charge and even what little metal there is exposed at the lower end of the rib is connected with an extensive radiating surface thus insuring a long life to the metal part of the structure. Even should one of the arch sections break for any reason, the broken parts are retained in the frames due to the fit between the side sills and these parts will not fall onto the moving charge.

It is practically impossible for the side sills to burn away and so long as the side sills last the fire blocks will be held in position. The upper edge of the side sills which 20 constitute the supports for the blocks are removed from the lower side of the blocks and are thus removed from the heating action of both the combustion chamber and from the fired charge on the sintering machine.

As the blocks can be readily demounted, new sections can be inserted in place in the frame as desired and even should part of the frame burn it is easy to replace the damaged part with but little interruption to the continued use of the device.

Having thus described my invention, I claim:—

1. In a device of the class described, a fire 35 resisting, open bottom arch construction having oppositely disposed upstanding walls, each of said walls provided on the outer sides thereof with a recess forming overhanging shoulders on opposite sides of the 40 arch construction, said shoulders adapted to rest on oppositely disposed sill elements of a supporting frame whereby the arch construction can be suspended in position.

2. In a device of the class described, a fire 45 resisting, open-bottom arch construction outlining the upper portion of a combustion chamber with the rise thereof decreasing from one end toward the opposite end and means for having the construction in position.

3. In a device of the class described, a fire 55 resisting, open-bottom arch construction outlining the upper portion of a combustion chamber with the rise thereof decreasing from one end toward the opposite end and having a cross sectional area intermediate the ends greater than the cross-sectional area adjacent the ends.

4. In a device of the class described, a fire 60 resisting, open-bottom arch construction outlining the upper portion of a combustion chamber with the rise thereof decreasing from one end toward the opposite end and having a cross-sectional area intermediate the ends greater than the cross-sectional

area adjacent the ends and means for hanging the construction in position.

5. In a device of the class described, the combination of a plurality of arch sections arranged in pairs interlocking along their 70 crowns and with one pair interlocking with the next adjacent pair at their contiguous ends thereby to form an open-bottom arch construction, the lower edges of each of said sections being exposed and disposed 75 substantially in a single plane whereby the open-bottom of the arch construction may be positioned close to the top of a traveling member.

6. In a device of the class described, an 80 open-bottom arch construction having a combustion chamber therein exposed downwardly through the open-bottom, said chamber having a combustion-fuel-entering end and said chamber decreasing the cross-sectional 85 area from said fuel entering end toward the opposite end.

7. In a device of the class described, an open-bottom arch construction having a combustion chamber therein exposed downwardly through the open-bottom, said chamber having a combustion-fuel-entering end and said chamber decreasing the cross-sectional area from said fuel entering end toward the opposite end and a depending 95 arch'd wall for substantially closing said opposite end.

8. An igniting device including an open end burner containing section closed along its bottom and a combustion chamber section opening from the burner section to receive the flame from the burner therein and exposed along its bottom to permit the flame to ignite substances positioned below said combustion chamber, the upper wall of said 105 combustion chamber being inclined downwardly from the burner section end toward the opposite end thereof whereby the flames impinging against said wall are deflected thereby downwardly through the open bottom.

9. An igniting device provided with a longitudinally extending combustion chamber open along its bottom side and provided at one end with a flame receiving inlet, said 115 chamber having a greater rise at the inlet than at the opposite end whereby the clearance for the burning is decreased as the gases are passed through the chamber thus tending to insure a uniform distribution of flame 120 throughout the length of the open bottom.

10. An igniting device provided with a longitudinally extending combustion chamber open along its bottom side and provided at one end with a flame receiving inlet, the 125 cross-sectional area of said chamber progressively decreasing from the inlet end toward the opposite end whereby tending to insure a uniform distribution of flame along the length of said open bottom, said chamber 130

having a greater rise at the inlet than at the opposite end whereby the clearance for the burning is decreased as the gases are passed through the chamber thus tending to insure 5 a uniform distribution of flame throughout the length of the open bottom.

11. In a sintering device having a chamber extending lengthwise thereof, one end of said chamber provided with a bottom for 10 closing the underside of the same to form a burner containing compartment at one end of said chamber and the part of the chamber beyond said compartment being exposed on its underside to permit flames in the chamber to pass therefrom and ignite substances positioned beneath the open bottom part, the outer end of said compartment provided with an opening permitting access to the 15 interior of the burner containing compartment 20 and a frame engaging the igniting device above the bottom thereof for supporting the same in the sintering machine.

12. In a sintering device having a chamber extending lengthwise thereof, one end of said chamber provided with a bottom for 25 closing the underside of the same to form a burner containing compartment at one end of said chamber and the part of the chamber beyond said compartment being exposed on 30 its underside to permit flames in the chamber to pass therefrom and ignite substances positioned beneath the open bottom part, the outer end of said compartment provided with an opening permitting access to the 35 interior of the burner containing compartment and a frame engaging the igniting device above the bottom thereof for supporting the same in the sintering machine, said burner containing compartment increasing 40 in span from said opening toward the flame inlet of the open bottom portion of the chamber.

13. In a sintering device having a chamber extending lengthwise thereof, one end of said chamber provided with a bottom for 45 closing the underside of the same to form a burner containing compartment at one end of said chamber and the part of the chamber beyond said compartment being exposed on 50 its underside to permit flames in the chamber to pass therefrom and ignite substances positioned beneath the open bottom part, the outer end of said compartment provided with an opening permitting access to the 55 interior of the burner containing compartment and a frame engaging the igniting device above the bottom thereof for supporting the same in the sintering machine, said burner containing compartment increasing in span 60 from said opening toward the flame inlet of the open bottom portion of the chamber, and said open bottom portion of the chamber decreasing in rise from said flame inlet end toward the opposite end.

14. In a device of the class described, the

combination with a hanging frame comprising a plurality of longitudinally spaced apart arch ribs, and a pair of longitudinally extending and transversely spaced apart side sills connecting the inner sides of said ribs, of arch sections fitted between said side sills and provided with shoulders spaced from the bottom of said sections positioned to rest on said sills, said sections coacting to form an open bottom combustion chamber 75 spaced from said hanging frame.

15. In a device of the class described, the combination with a supporting frame including a pair of inverted U-shaped arch ribs and side sills connecting adjacent sides 80 of each rib above the lower ends thereof, arch sections fitted within said ribs, supported above the bottom thereof on said side sills and coacting to form a combustion space closed along its top and open through its 85 bottom side.

16. In a device of the class described, the combination of a supporting frame provided with means for hanging the same in place, a plurality of arch sections demountably positioned in said frame and arranged to form an open bottom arch construction forming a combustion chamber therein exposed through said open bottom and closed along the top thereof, said sections formed of fire-resisting 95 material and disposed to protect the frame from the heat in the chamber.

17. In a device of the class described, the combination of a supporting frame including longitudinally disposed side sills fixed 100 relative to each other in spaced apart position, arch sections supported at their sides on said sills and contacting along their crowns, said sections coacting to form a combustion space and acting to protect the 105 frame from the heat in said space.

18. In a device of the class described, the combination of a supporting frame including longitudinally disposed side sills fixed 110 relative to each other in spaced apart position, an arch construction fitted between and supported by said side sills, said construction forming a combustion chamber provided with an open bottom and said construction closed along its crown whereby burning gases in said chamber are caused to move 115 therefrom downwardly out through said bottom end and out of contact with said sills.

19. In a device of the class described, the combination with a supporting frame including a pair of inverted U-shaped arch ribs and side sills connecting adjacent sides 120 of each rib above the lower ends thereof, arch sections fitted within said ribs, supported above the bottom thereof on said side sills 125 and coacting to form a combustion space closed along its top and floor blocks separate from the arch section fitted between and supported by said ribs and closing the bottom of said combustion space.

20. In a device of the class described, the combination of an igniting device formed of fire resisting material and provided with a flame distributing opening in its underside 5 and a metallic frame for supporting said device in suspended position, said frame being of openwork construction with relatively large heat discharging areas and spaced from said bottom opening to remove the 10 same from flames discharged through said opening.
21. In a device of the class described, the combination with a skeleton metal frame, of a block construction fitted within said frame 15 and having a combustion chamber therein with an opening through the bottom thereof, said construction including a plurality of pairs of interlocking blocks of fire resisting material, the blocks of each pair
- locked in position by said frame against an 20 outward separating movement.
22. In a device of the class described, the combination with a skeleton metal frame, of a block construction fitted within said frame and having a combustion chamber 25 therein with an opening through the bottom thereof, said construction including a plurality of pairs of interlocking blocks of fire resisting material, the blocks of each pair locked in position by said frame against an 30 outward separating movement and all parts of the frame which act to support the blocks forming the opening being positioned above the plane of the opening.

Signed at Helena in the county of Lewis 35 and Clark and State of Montana this 18th day of April, A. D. 1919.

ROGER L. STROBEL.
